UNITED STATES PATENT OFFICE

2,579,989

RADIO ENERGIZED LAMP

Nathaniel B. Wales, Jr., New York, N. Y.

Application December 1, 1949, Serial No. 130,421

1 Claim. (Cl. 315—188)

1

This invention relates to a lighting device, especially a table lamp, in which the power for energizing the lamp is transmitted thereto by electromagnetic radiation.

This device is particularly useful in restaurants and public places where the absence of power wires and the obscurity of its power source are valuable from convenience and novelty standpoints.

In my invention I utilize a loop inductance in conjunction with a capacitance to form a tunable resonant circuit, preferably parallel, to energize an electric light, preferably of the fluorescent gaseous discharge type. The electromagnetic radiation for powering this lamp may be generated by a crystal-controlled oscillator-amplifier, operating on some authorized industrial frequency, and radiated by a dipole unobtrusively located near the ceiling of the restaurant or auditorium to be lighted. In the preferred form of the invention I utilize the inductive loop as the mechanical support for this fluorescent lamp. This double utility permits the linking of the radiation field by a substantial "aperture" while occupying a minimum of table space for the lamp. In addition, the vertical plane of such a loop-support permits the maximum average energy transfer from a dipole elevated above such lamps, since the vertical plane of the loops may be made more closely to coincide with a plane passing through the dipole than any other fixed geometry of loop.

It is to be noted that this loop-support concept is equally applicable to a less preferred form of my invention utilizing a series resonant circuit in conjunction with an incandescent lamp.

A particularly valuable feature of the invention lies in the use of an auxiliary starting electrode external to the gaseous discharge tube and so positioned that, prior to the initial breakdown of the gases in the tube, there is a concentration of the oscillatory potentials appearing across the resonant circuit applied through a small portion of the operating gap of this discharge tube. This results in a very large decrease in the power necessary to start the lamps over a given distance, below that which would be required without this field concentration. Evidently, this step makes the installation of such lamps more practical from an equipment cost standpoint.

An object of this invention is to make possible a remotely-powered light source having no wire connections.

A second object is to combine the elements of a large aperture resonant circuit with the components of a table lamp with a minimum of parts.

2

A third object is to make possible a radio-powered gaseous discharge lamp which does not require excessive power for starting.

Other objects will appear in the specifications and claim.

Referring to the drawings:

Figure 1 is the schematic diagram of one form of radiating system suitable for energizing my invention;

Figure 2 shows a vertical section in elevation of the preferred form of my invention;

Figure 3 is the section 3—3 of Figure 2;

Figure 4 is the schematic wiring diagram of the device shown in Figure 2; and

Figure 5 is a detailed enlargement of the condenser 3 shown in Figure 2.

The preferred type of radiator installation shown in Figure 1 consists of a crystal-controlled oscillator 18 feeding a power amplifier 19 which in turn feeds the dipole elements 23 via the transmission line 20. The wires 23 are secured to center insulator 21 and end insulators 22. Guy wires 24 secure the end insulators 22 to the walls 26 by means of screw-eyes 25. It is desirable that the walls 26 and ceiling 27 be of a metal lath or other construction which will be reflective at the frequency of oscillator 18, so that a minimum of radio-frequency energy is radiated beyond the room to be lighted.

Such other precautions well-known to the art, such as the use of Faraday shields, push-pull stages, filtered power supplies, and no frequency doubling, should be used to prevent the radiation of harmonics, thereby insuring the confinement of the radiation to the authorized frequency band (for instance, 27 megacycles).

The receiving lamp shown in Figures 2, 3, 4 and 5 consists of a circular metal (copper) loop 1 passing through and secured to the base 2 which is preferably made of a transparent plastic. This transparent construction emphasizes the absence of concealed wires in the device.

Loop 1 within the scope of this invention may also be rectangular or of any other artistically desirable shape as long as it subtends an adequate area and presents a sufficiently high electrical Q to operate its lamp. A circular loop gives the maximum Q for this class of geometry.

The ends of loop 1 connect and are secured to the support leads or buses 6 and 8 which in turn connect and are secured to the opposite end terminals of the fluorescent gaseous discharge tube 9. Tube 9 is operated as a two electrode cold cathode discharge tube, as shown in Figure 4.

However, for convenience in availability, a standard commercial hot cathode fluorescent

tube may be used in the capacity of a cold cathode tube, as shown. In this case, it is permissible to short circuit together the two pin terminals 10 on each end, as shown in Figure 3, thereby using each of the two filament circuits on each end of such a tube as a single "cold" discharge electrode.

The conventional variable air condenser 3 consists of shaft 3, rotor plates 15, bushing 16, knob 4 mounted on shaft 3, insulating plate 17, stator support 13 and stator plates 14. This unit is secured between the ends of the loop 1 by bracket 12 on one side and by stator support 13 via bus 6 on the other side, thereby also making the parallel electrical connection shown in Figure 4. The non-metallic truncated conical shade 5 is secured to the insulating condenser plate 17 by screws 11, thus completing the lamp structure proper. Obviously, other forms of shades or positions of the tube may be used under the scope of the invention. For instance, the shade may be the segment of a small long cylinder and cover the tube alone; or the segment of a short large cylinder and cover the upper portion of the whole loop. Similarly, the tube may be radial (internally or externally) or normal to the plane of the loop.

The preferred means for causing a high space gradient of the potentials appearing across the resonant circuit to be set up within a portion of the discharge tube for easy starting is shown in Figure 2 as the conductive rod 7 which comprises an extension of the support conductor 6. This auxiliary electrode 7 terminates a short distance from the end of the tube opposite its junction with bus 6 and, consequently, a high gradient of the potentials across the parallel resonant circuit will be set up between the tip of electrode 7 through the glass wall of the tube to the adjacent electrode within tube 9. This high local gradient will ionize the gas within the tube at a far lower resonant peak potential than that needed to ionize gas using the gradient which would obtain across the whole tube in the absence of auxiliary external electrode 7. Once electrode 7 has created local ions within the tube, cumulative ionization within the tube will cause the entire tube to break down, thus affording a low impedance path for

the resonant currents, in contradistinction to the high impedance path offered through the internal electrodes of the tube prior to breakdown.

Alternative to this particular execution of the invention, it is equally operable to form the leads 6 and 8 so that they are sufficiently adjacent both to the glass wall of tube 9 and to one another as to apply a concentrated field across a central portion of the whole breakdown gap 10-10 (Figure 2) thereby achieving the same end. In either case, electrode means external to the discharge tube are utilized to produce a potential gradient across a portion of the operating discharge gap.

What I claim is:

In a lamp structure adapted to be energized by absorbed radio-frequency energy, the combination comprising a lamp base, a substantially circular metallic arc secured at its mid-portion to said base, the upwardly extending arms of said arc lying in a vertical plane and forming an inductive loop member for absorbing said radio-frequency energy, a tubular gaseous discharge tube, two electrodes entering said tubular discharge tube at opposite ends thereof, a metallic member for securing each of said electrodes to the opposite ends of said arc whereby to support said tube and electrically connect it in parallel with said inductive arc member, an adjustable capacitance connected in parallel with said loop member, and a starting electrode located exterior to said discharge tube closely adjacent to one end thereof and electrically connected to that first said electrode lying at the opposite end of said discharge tube from said starting electrode.
